UNITED STATES PATENT OFFICE.

JAY J. DAVIS, OF APOLLO, PENNSYLVANIA.

LIFTING AND CONVEYING APPARATUS.

Application filed December 22, 1925. Serial No. 76,970.

This invention relates to lifting apparatus and more in particular to lifting devices adapted to be used in connection with the careful handling of materials in sheet-form, such as glass-sheets, metal-sheets or other materials having at least one flat and smooth surface.

The primary object of this invention is to provide a lifting apparatus adapted for lifting, by means of vacuum operated lifting means, sheets of steel, glass or other materials which require careful handling to prevent scratching or otherwise marring said materials when transported from one place to another, or when being stacked into piles in shops or warehouses. Another object of this invention is to provide means whereby said materials may be quickly released from the lifting apparatus by means of a unitary releasing means. A further object is to provide an apparatus comprising a plurality of vacuum-cups which may be applied to the goods to be lifted simultaneously and by means of the weight proper of said apparatus. Additional features and advantages of this invention will appear from the following description considered in connection with the accompanying drawing forming a part of this application and in which:—

Fig. 1 is a top plan view of a lifting apparatus built according to my invention and adapted to lift sheets of steel or glass of large size.

Fig. 2 is a side elevation of Fig. 1.

Fig. 3 is a front elevation of Fig. 1.

Fig. 4 is an enlarged section through a suction cup, taken on line 4—4 in Fig. 1.

Fig. 5 is a view showing a modification of the suction cup used in my lifting apparatus.

Fig. 6 shows a lifting device provided with a single lifting cup and adapted especially to lift small sheets, plates, or small barrels having flat and smooth ends.

Reference being had to the drawing, the lifting and handling of goods by the apparatus is performed by means of vacuum-cups, the number and size of which is determined by the weight and size of the sheet-like goods which are to be handled. As shown in Fig. 4, especially, the preferred construction of the vacuum-cups comprises a shell 1 of rubber having substantially the

shape of a spherical segment and provided with an upwardly directed circular flange 2 and with a central hub 3 in which a cylindrical depression 4 is formed to receive the spherical end, 5 of the lifting-rod 6 which is mounted for vertical sliding movement in a guide-block 7 secured on the underside of the frame-bar 8 which is also suitably apertured to act as an additional guide for said lifting-rod. The upper end 9 of the latter is threaded and protrudes above the frame-bar to engage a coil-spring 10 which is inserted between the two washers 11 and 12 and the tension of which may be regulated and maintained by means of the nut 13 and the lock-nut 14. The vacuum-cup is secured on the lifting-rod by means of the clamping device 15 which is suitably placed above the spherical portion of the lifting-rod to enable the cup to rock about said portion in all directions, the purpose of this being to enable the vacuum-cup to adjust itself more readily to the surface of the material to be lifted.

The numerous vacuum-cups required to lift a large sheet of material are mounted and evenly distributed upon a very rigid frame 16 consisting of the frame-bars 8 and the cross-bars 17. The weight of this frame must be sufficiently great to cause the collapse of all the vacuum-cups when brought to rest upon them, so that the air may be expelled from said cups simultaneously. The vacuum created under the cups causes a sheet to adhere to them due to the action of the atmospheric pressure and the frame, with the sheet, may be transported in the air from one place to another one where the sheet is to be deposited.

In order to prevent any accident in the unloading of a sheet, the latter must be released from all the suction-cups at the same time. This is achieved in my invention by means of the following mechanism: Adjacent each vacuum-cup 1 there is provided a finger, or dog, 18 hingedly mounted in a support 19 secured on the underside of the frame 16. The lower end of each finger is provided with a protuberance, or nose, 20 adapted to engage the underside of the flange 2 and lift the latter a sufficient amount to enable the air to enter the cup and break the vacuum.

The dogs in the same frame-bar are mounted in a straight row and are operated simultaneously by the common push-rod 21

which is suitably guided for sliding movement in the brackets 22, also secured on the under-side of the frame 16.

The simultaneous operation of the various push-rods of the lifting device is performed by means of an operating-lever 23 secured at the end of the operating-shaft 24, mounted for rotation in the bearing-supports 25 and 26 secured in any desired manner on the front cross-bar of the frame. Upon this shaft are keyed, or otherwise fastened, the levers 27 the lower ends 28 of which are forked and connected to the forward ends of their corresponding push-rods, by means of the pin and slot connections 29. A similar connection 30 is also shown to connect the various dogs to their common push-rod. The operating-lever 23 is normally held in the neutral, or horizontal, position shown in Fig. 2 by means of any desired and suitable device, such as the coil-spring 31 surrounding the operating-shaft and having one end secured thereto whereas the other end bears against the front cross-bar. The complete apparatus, is moved from one place to another by means of a crane, or other lifting apparatus, to which it is attached by means of chains or cables which are connected to suitable hooks 32 provided at the four corners of the apparatus.

The purpose of the coil-springs 10 around the lifting-rods 6 of the vacuum-cups is to prevent any sudden jars on the latter at the time when the frame with a suspended sheet of material is just being lifted. This feature is especially helpful in cases when the lifting of the frame at the four corners is not exactly equal so that the frame assumes a somewhat inclined position. The strength of the springs is so proportioned that they will give a sufficient amount to overcome any such difference of level and thus maintain the sheet in proper engagement with the suction cups.

In the modified construction shown in Fig. 5, the vacuum-cup 33 is provided with several lugs 34, instead of the circular flange 2, for reasons of economy in the rubber material and to give the vacuum-cup greater flexibility around the edge. This construction, however, requires a fixed relation between the cup and the dogs, which is not necessary with the full circular flange, as will be readily understood.

When applied to small goods of rather reduced weight, such as small metal barrels or tin containers, an apparatus with a single vacuum-cup may be found satisfactory. In Fig. 6 is illustrated such a device which consists of the vacuum-cup 35, of similar design as shown in Fig. 5, and which is rockably connected by means of the spherical joint 36 to the lower end of the lifting-rod 37 which carries at its top the lifting-eye 38,

by means of which the device may be lifted by a crane. The size of the pear-shaped weight 39 is such that it will collapse the vacuum-cup to drive out the air therefrom. The vacuum in the cup is broken by pulling on the chain 40 secured at one end to the weight and at the other end to one of the lugs 41. The initial lifting jars are absorbed by the coil-spring 42 placed around the lifting-rod between the weight and the lifting-eye.

In order to relieve the vacuum-cups of the weight of the apparatus when not in use and stored away, I provide adjacent each corner of the frame the legs 43 which are hingedly mounted on pins 44 and which are made long enough to enable the vacuum-cups to clear the floor when the frame rests on said legs. When the apparatus is in use, the legs may be quickly folded up, out of the way, in the position shown in dot and dash lines in Fig. 2. The legs are maintained in the selected position by means of pins 45 insertable in suitable registering apertures 46 and 47 provided in the legs and frame respectively.

Having described the principal parts of my invention, its operation will be readily understood and may be succinctly stated as follows:—Assuming that sheets of steel, as they come from the rolling-mills, are to be stacked up into piles, the lifting apparatus is brought over each individual sheet by means of a crane and then dropped slowly over the sheet so that the weight of the frame of the apparatus will cause all the vacuum-cups to collapse, thus expelling the air therefrom. The complete apparatus with the suspended sheet is now lifted and transferred by the crane to the place of stacking and lowered close to the pile of sheets, after which the workman pulls the operating-lever 23 which causes all the vacuum-cups to open up simultaneously, thereby allowing the sheet to drop off the lifting apparatus directly on the pile. The apparatus is then returned to the rolling-mill and the same performance is repeated until the stacking is completed.

It will be understood, of course, that the arrangements I have herein shown are merely suggestive of many that might be adopted in carrying out my invention, and I do not wish to be limited to the constructions illustrated otherwise than as specified in the appended claims.

I claim:—

1. In a lifting apparatus, a plurality of resilient vacuum-cups; a unitary frame therefore of sufficient weight to cause the collapse of said cups when resting thereon to form a vacuum thereunder, and lever operated means to break said vacuum under said cups by temporarily lifting a part of the circumference thereof.

2. In a lifting apparatus, a plurality of

resilient vacuum-cups; a unitary frame therefor of sufficient weight to cause the collapse of said cups when resting thereon to form a vacuum thereunder, and lever operated means to break said vacuum under said cups by simultaneously lifting a part of the circumference thereof.

3. In a lifting apparatus, the combination of a plurality of resilient vacuum cups; a unitary frame therefor of sufficient weight to cause the collapse of said cups when resting thereon to form a vacuum thereunder; additional means for supporting said frame independently of said vacuum-cups, and lever operated means for breaking said vacuum under said cups by temporarily lifting a part of the circumference thereof.

4. In a lifting apparatus, the combination of a plurality of resilient vacuum-cups; a unitary frame therefor of sufficient weight to cause the collapse of said cups when resting thereon to form a vacuum thereunder; additional foldable means for supporting said frame independently of said vacuum-cups, and unitary lever operated means to break said vacuum under said cups simultaneously by temporarily lifting a part of the circumference thereof.

5. In a lifting apparatus, the combination of a plurality of resilient vacuum-cups; a unitary frame therefor of sufficient weight to cause the collapse of said cups when resting thereon to form a vacuum thereunder.

6. In a lifting apparatus, the combination of a plurality of resilient vacuum-cups; a unitary frame therefor of sufficient weight to cause the collapse of said cups when resting thereon to form a vacuum thereunder; a hinged dog positioned adjacent each of said vacuum-cups and unitary means to cause said dogs to simultaneously and temporarily lift a part of the circumference of said cups to break the vacuum thereunder.

7. In a lifting apparatus, the combination of a plurality of resilient vacuum-cups; a unitary frame therefor of sufficient weight to cause the collapse of said cups when resting thereon to form a vacuum thereunder; a hinged dog positioned adjacent each of said vacuum-cups; a lever adapted to cause said dogs to simultaneously and temporarily lift a part of the circumference of said cups to break the vacuum thereunder, and means to return said lever into normal or inactive position.

In testimony whereof I affix my signature.

JAY J. DAVIS.
